(57) **CLAIM**

The ornamental design for a catheter device for radiofrequency ablation, as shown and described.

DESCRIPTION

FIG. 1 is a front view of a catheter device for radiofrequency ablation in accordance with the present invention;

FIG. 2 is a rear view of the catheter device for radiofrequency ablation in accordance with the present invention;

FIG. 3 is a top view of the catheter device for radiofrequency ablation in accordance with the present invention;

FIG. 4 is a bottom view of the catheter device for radiofrequency ablation in accordance with the present invention;

FIG. 5 is a right side view of the catheter device for radiofrequency ablation in accordance with the present invention;

FIG. 6 is a left side view of the catheter device for radiofrequency ablation in accordance with the present invention;

FIG. 7 is a perspective view of the catheter device for radiofrequency ablation in accordance with the present invention;

FIG. 8 is an enlarged view taken from FIG. 1;

FIG. 9 is an enlarged view taken from FIG. 2;

FIG. 10 is an enlarged view taken from FIG. 3;

FIG. 11 is an enlarged view taken from FIG. 4;

FIG. 12 is an enlarged view taken from FIG. 5;

FIG. 13 is an enlarged view taken from FIG. 7;

FIG. 14 is an enlarged view taken from FIG. 1;

FIG. 15 is an enlarged view taken from FIG. 4; and,

FIG. 16 is an enlarged view taken from FIG. 13.

The dotted lines in the drawings illustrate portions of the catheter for radiofrequency ablation and form no part of the

(Continued)

claimed design. The thin line and dot configurations in the figures represent surface shading. The dot-dot-dash broken lines in the drawings represent boundaries of the enlarged portions and forms no part of the claimed design.

1 Claim, 16 Drawing Sheets
